UNITED STATES PATENT OFFICE.

ROBERT D. SIMPSON, OF COLUMBUS, OHIO, ASSIGNOR TO THE COLUMBUS STEEL PRODUCTS COMPANY, OF COLUMBUS, OHIO, A CORPORATION OF OHIO.

SUPPORT FOR METERS.

1,315,244.

Specification of Letters Patent. Patented Sept. 9, 1919.

Application filed January 2, 1919. Serial No. 269,320.

To all whom it may concern:

Be it known that ROBERT D. SIMPSON, a citizen of the United States, residing at Columbus, in the county of Franklin and State of Ohio, has invented certain new and useful Improvements in Supports for Meters, (division of my application Serial Number 189,443, filed September 4, 1917,) of which the following is a specification.

This invention relates to supports for meters, particularly gas meters, and is designed to properly support the same to relieve the meters themselves from any undue strain. My invention therefore has for its main object a shelf structure for so supporting the meter from its connections that the likelihood of breaking or warping of the meter connections is reduced to a minimum. In this connection, it is also my object to reduce the amount of labor necessary in setting a meter to a minimum.

The preferred embodiment of my invention is shown in the accompanying sheet of drawing in which similar characters of reference designate corresponding parts and in which the figure shows a conventional type of gas meter suitably connected and supported by my improved type of shelf structure.

In this figure, the gas meter as a whole is designated by the reference numeral 1 and is shown as being provided with the conventional type of inlet and outlet pipes 2 and 3. To these connections, there is secured a meter attachment of the form shown and claimed in my Patent No. 1,284,160 dated November 5, 1918. This attachment includes suitable fittings 4 and 5 connected to the meter as shown and provided with unions 6 at their upper ends for direct attachment to the gas inlet and outlet pipes shown at 7 and 8. Each of the fittings 4 and 5 is also provided with a laterally projecting ear 9 which is pierced for pivotal connection with the transverse connection formed of the telescopic sections 10 and 11. The section 10 is shown as being pivotally mounted to the fitting 4 at 12 while the section 11 is connected to the opposite fitting as shown at 13. The opposite end of this section 11 is slotted as shown at 14 and is also provided with a series of threads to accommodate the nut 15 so that after the parts have been assembled and adjusted to their natural positions to accommodate any slight varia-

tions in alinement of the pipes 2 and 3, the entire structure may be securely locked against injurious distortion. The portion of the structure thus far described does not form the novel features of the present invention but is claimed in my patent referred to above wherein the various advantages are fully set forth.

Each of the fittings 4 and 5 is provided with a second pierced ear 16 which forms a means of supporting my novel shelf structure. As shown in the present drawing, this support is formed of a rod 17 bent to U shape to properly fit the underside of the meter and is threaded at its two extremities as shown at 18. Turn buckles 19 are provided and are screwed onto these threaded ends and also carry hooked rods 20 at their opposite ends. These hooked rods in turn are secured to springs 21 which latter are in turn anchored to the pierced ears 16 after the manner shown. By means of the springs, the shelf supporting structure may be drawn tightly against the underside of the meter and inasmuch as these springs are supported from the fittings 4 and 5, the strain on the inlet and outlet pipes attached to the meter itself is entirely relieved. Further, tension of these springs may be varied at will so that they may be made to exert like pulls by properly adjusting the turn buckles 19. By this arrangement, the entire structure connected to the meter may be described as being self contained and the shelf itself occupies a minimum of space, has a pleasing appearance and at the same time is thoroughly practical in operation. When properly adjusted, no strains whatever need remain in the meter pipes 2 and 3 so that the user may be assured against breaks of the meter from this source. Further, by selecting the proper springs and tensioning them so that they exert a pull greater than that of the weight of the meter, a resultant pressure is produced in the form of compression between the fittings 4 and 5 and the meter proper which will operate to automatically compensate for any shrinkage in any gaskets used and will eliminate the probability or tendency of any unscrewing of the threaded connections thus materially reducing the likelihood of any leaks.

What I claim is:

1. The combination with a meter of fit-

tings for the inlet and outlet thereof, a shelf supporting structure for the meter suspended from said fittings, and spring means forming a portion of said structure arranged to pull the supporting structure toward said fittings in opposition to the weight of the meter.

2. The combination with a meter, of fittings for the inlet and outlet thereof, a shelf supporting structure for the meter suspended from said fittings, spring means forming a portion of said structure arranged to pull the supporting structure toward said fittings in opposition to the weight of the meter, and means whereby the tension of said spring means may be varied.

3. The combination with a meter and means for securing it to its pipe lines, of a shelf supporting structure for the meter op-

eratively located between the meter and its pipe lines, and spring means forming a portion of said structure and arranged to exert a pull on the meter toward its pipe line connections in opposition to the weight of the meter.

4. The combination with a meter and means for securing it to its pipe lines, of a shelf supporting structure for the meter operatively located between the meter and its pipe lines, spring means forming a portion of said structure and arranged to exert a pull on the meter toward its pipe line connections in opposition to the weight of the meter, and means for varying the tension of said springs.

In testimony whereof I affix my signature. 35

ROBERT D. SIMPSON.
